United States Patent

Des. 240,501
Patented July 13, 1976

240,501

SIGN CLIP

Richard A. Carroll, North Providence, R.I., assignor to
The Lorac Company, Inc.

Filed Apr. 7, 1975, Ser. No. 565,758

Term of patent 14 years

Int. Cl. D8—08

U.S. Cl. D8—245

FIG. 1

FIG. 2

FIG. 3

FIG. 4

FIG. 5

FIG. 6

FIG. 1 is a front elevational view of a sign clip showing my new design;

FIG. 2 is a side elevational view thereof;

FIG. 3 is a rear elevational view thereof;

FIG. 4 is a top plan view thereof;

FIG. 5 is a bottom plan view thereof; and

FIG. 6 is a front perspective view thereof.

I claim:

The ornamental design for a sign clip, substantially as shown.
